UNITED STATES PATENT OFFICE.

OTTO L. HEMMING, OF NEW HAVEN, CONNECTICUT, ASSIGNOR, BY MESNE ASSIGNMENTS, TO THE F. B. SHUSTER CO., OF NEW HAVEN, CONNECTICUT, A CORPORATION.

RIVETING-MACHINE.

1,054,544.

Specification of Letters Patent. Patented Feb. 25, 1913.

Application filed July 22, 1912. Serial No. 710,919.

To all whom it may concern:

Be it known that I, OTTO L. HEMMING, a citizen of the United States, residing at New Haven, in the county of New Haven and 5 State of Connecticut, have invented a new and useful Improvement in Riveting-Machines; and I do hereby declare the following, when taken in connection with the accompanying drawings and the characters of 10 reference marked thereon, to be a full, clear, and exact description of the same, and which said drawings constitute part of this application, and represent, in—

Figure 1 a side view with a part of the 15 head broken away, of a riveting machine showing my improved counterbalance applied thereto. Fig. 2 a sectional view on the line *a—b* of Fig. 1. Fig. 3 a broken side view to illustrate the substitution of springs 20 for the weight.

This invention relates to an improvement 25 in riveting machines, and more especially to riveting machines of the larger type. In the use of these machines the jar or vibration is so great that it is usually necessary to set up the machines on a very firm bed, and their use in upper stories of most buildings is dangerous.

The object of this invention is to provide 30 a counterbalance which will overcome vibration; and the invention consists in the construction hereinafter described and particularly recited in the claim.

Secured to the head 2 of a riveting machine of usual construction, I mount a 35 bracket 3 in which is pivoted a lever 4 the forward end of which is connected with the

hammer. This is preferably done by coupling the lever to the usual nut 6 which is connected with the slide or cylinder 9 40 through which the revolving hammer rod 5 extends. At the opposite end of the lever I attach a weight 7. This weight will vary in varying sizes of machines and is of such a weight as to counterbalance the spring 45 chamber and hammer rod and hence prevent the jar or vibration of the machine. It is apparent, and as indicated in Fig. 3, that instead of connecting the weight 7 on the end of the lever 4, that the end of the lever 50 4 may be connected with the frame of the machine by springs 8. A counterbalancing lever thus described, not only prevents vibration and enables riveting machines to be used on any floor, but also by preventing 55 vibration enables the machine to be driven at very much higher speed.

I claim:—

In a riveting machine, the combination 60 with the head, the slide and the hammer rod, of a counterbalancing lever pivotally mounted on the head and connected at one end with said slide, and means applied to the other end of said lever for counterbalancing the weight of the said slide and 65 hammer rod.

In testimony whereof, I have signed this specification in the presence of two subscribing witnesses.

OTTO L. HEMMING.
